* cited by examiner

Primary Examiner — Abraham Bahta(74) *Attorney, Agent, or Firm* — Stetina Brunda Garred & Brucker(57) **CLAIM**

The ornamental design for an auto recall notice postcard, as shown and described.

DESCRIPTION

A portion of the disclosure of this patent document contains material which is subject to (copyright or mask work) protection. The (copyright or mask work) owner has no objection to the facsimile reproduction by anyone of the patent disclosure, as it appears in the Patent and Trademark Office patent files or records, but otherwise reserves all (copyright or mask work) rights whatsoever.

FIG. 1 is a perspective view of a postcard;

FIG. 2 is a front view of the postcard of FIG. 1; and,

FIG. 3 is a rear view of the postcard of FIG. 1.

The auto recall notice postcard has no appreciable thickness.
